[57] CLAIM

The ornamental design for a container for pacifiers, as
shown.

DESCRIPTION

FIG. 1 is a front elevational view of a container for
pacifiers, showing my new design;

FIG. 2 is a rear elevational view;

FIG. 3 is an end elevational view taken from the right of
FIG. 1;

FIG. 4 is an end elevational view taken from the left of
FIG. 1;

FIG. 5 is a top plan view;

FIG. 6 is a bottom plan view; and,

FIG. 7 is a perspective view of said container.

FIG. 1

FIG. 2

FIG. 3
